ANESTHESIA AND SURGERY RESTRAINING DEVICE

Ralph Gilbert Peterson, Minneapolis, Minn.

Application October 9, 1944, Serial No. 557,743

7 Claims. (Cl. 128—134)

1

This invention relates to devices for restraining patients who undergo anesthesia and/or surgery.

In many cases of surgery and particularly dental surgery, the patient will react nervously to the anesthetic and make it difficult for the surgeon to properly execute his work.

In my prior Patent Number 2,295,806, issued September 15, 1942, there is disclosed a restraining device for the same purpose. Nervous reactions of this type are particularly prevalent among children but such conditions are also encountered with adult patients.

While the apparatus disclosed in my above mentioned patent is highly effective, it is a general object of this invention to provide a restraining device which is more simple in its structure and application to the patient.

In one form of the invention, I provide means for securing the wrists and holding them against the body with the hands together in simulation of a natural sitting position.

In another form of the invention, I provide means for restraining a reclining patient with the arms held at the sides.

The above and other objects of the invention will more fully appear from the following description made in connection with the accompanying drawing wherein like reference characters refer to the same parts throughout the views, and in which;

Fig. 1 is a partial view of a patient with one form of restrainer applied;

Fig. 2 is a view similar to Fig. 1 with a different embodiment of my invention.

Fig. 3 is a perspective view of the restraining device of Fig. 1; and

Fig. 4 is a perspective view of the restraining device shown in Fig. 2.

In Figs. 1 and 3 there is shown a main body strap 5 which is adapted to encircle the waist or lower trunk portion of the patient. The strap 5 is provided with a buckle 5a at one end thereof, so that the strap can be secured about the patient. Mounted upon the main body strap 5 is a pair of wrist engaging or encircling strap sections 6. These strap sections may be formed of one piece of strap material or they may be of separate pieces having adjacent ends secured to an intermediate portion of the body strap 5 as shown at 7.

Adjacent the secured ends of the strap sections 6 the main body strap 5 is provided with transversely disposed diagonal elongated apertures 8, through which the free ends 9 of the strap sections 6 can be passed. It should be noted that the diagonally disposed apertures 8 are at angles

2

to each other and that the secured ends of the sections 6 are diagonally connected to the body strap 5, the direction of the line of connection of each section being parallel to the longitudinal direction of the aperture 8 of the respective section.

Adjacent their free ends, the wrist encircling strap sections 6 are provided with socketed fastener heads 10 which are adapted to cooperate with fastener members on the body strap 5. The details of the fastener elements are not shown but may conveniently be head and socket snap fasteners such as are manufactured by United-Carr Fastener Corporation of Cambridge, Mass. They can be quickly separated by pulling the free end 9 of each strap section 6 outwardly from the face of the body strap 5 and of course, can be connected by pressing them toward each other in a reverse direction.

20 The main body belt 5 is adapted to be first placed around the waist or lower body portion of the patient with the wrist encircling strap sections 6 located at the front of the body. The wrist encircling sections 6 are loosened, by pulling 25 on the free ends 9 of said sections, from the cooperating fastener elements on the main body portion 5. The hands of the patient can then be inserted through the loops formed by the wrist encircling sections 6, which can be drawn 30 through the apertures 8 in the main belt 5 until the wrists of the patient are tightly held in said wrist encircling sections 6. The free ends 9 of the strap sections 6 are then fastened to the main belt 5 by means of the snap fastener members 10 35 and the arms of the patient are thus tightly held against his body. The position of the patient's arms is illustrated in Fig. 1.

By reason of the fact that any pull on the wrist encircling strap sections 6 is transmitted through 40 the main belt apertures 8 and thence along the main body belt 5, any pull or movement exerted by the arms of the patient will be transferred to the snap fasteners 10 in a direction normal to the direction of release of said snap fastener. This 45 firmly retains the wrist encircling strap sections 6 and prevents the patient from disconnecting the fastener elements 10 from the main body belt 5 through any movement exerted on the loops which comprise the wrist encircling sections 6.

50 In Figs. 2 and 4 there is shown a modified form of the structure shown in Figs. 1 and 3. There is illustrated, a main body belt 11 corresponding to the body belt 5 of Figs. 1 and 3. Secured to the belt 11 is a pair of wrist encircling strap sections 12 each having one end secured to the main

strap 11 as by stitching 13. The free ends of the belt sections 12 are shown extended through elongated apertures 14 which are positioned across the main belt 11 at right angles to its length. The free ends 15 of the wrist encircling straps 12 are provided with snap fastener elements 16 similar to the elements 10 on the strap sections 6 of Figs. 1 and 3.

In the above described embodiment of the invention shown in Figs. 2 and 4, the anchored ends of the strap sections 12 are spaced apart and the free ends of the straps 12 are directed toward each other. In the device of Figs. 1 and 3, the anchored ends of the strap sections 6 are adjacent each other and their free ends 9 extend away from each other. By reason of the arrangement of the wrist encircling strap sections 12, it is possible to place the main body belt 11 about the patient and fasten the strap sections 12 about the wrists with the arms of the patient lying approximately along his sides. This structural arrangement is convenient where the patient is reclining whereas that shown in Figs. 1 and 3 is better adapted for a person who is seated in a more or less upright position such as he normally assumes in a dental chair.

The restraining devices shown and described can be quickly and easily applied to a patient without causing too great a psychological effect and while the snap fasteners 10 and 16 are arranged to firmly secure the straps encircling the wrists, they can be quickly released by the operator by merely pulling the free ends 9 and 15 of the strap sections 6 and 12 outwardly from the main body straps 5 and 11.

It should be noted that in Figure 1 the apertures 8 in the body strap 5 which are adapted to receive the wrist encircling strap sections 6, are placed on a diagonal and that the secured ends of the strap sections 6 are similarly positioned to cause the strap sections to assume a comfortable angle relative to the converging arm position of the patient as shown in Fig. 1. The device of Figs. 2 and 4 is provided with apertures 14 extending straight across the body strap 11 to properly position the wrist encircling strap loop sections 12 where the arms of the patient extend relatively straight along his sides.

It will of course, be understood that various changes may be made in the form, details, arrangement and proportion to the various parts without departing from the scope of this invention.

What I claim is:

1. In a restraining device for anesthesia and surgery, a main restraining belt, and a pair of wrist encircling belt sections, each of said sections having an end secured to said main belt, said sections having their other ends passed through said main belt in slidable relation thereto at points adjacent the secured ends of said sections, those portions of said sections extending through said main belt lying substantially flat against said main belt, and separable fasteners detachably connecting said extending portions of said sections to said main belt, and said fasteners being separable in a direction substantial-

ly transversely to said main belt and said extending portions of said sections.

2. In a restraining device for anesthesia and surgery, a main restraining belt, a pair of wrist encircling belt sections, each of said sections having an end secured to said main belt, said sections having their other ends passed through said main belt in slidable relation thereto at points adjacent the secured ends of said sections, those portions of said sections between their secured ends and their points of passage through said main belt providing wrist encircling loops lying closely adjacent to each other, those portions of said sections extending through said main belt lying substantially flat against said main belt, and separable fasteners detachably connecting said extending portions of said sections to said main belt, and said fasteners being separable in a direction substantially transversely to said main belt and said extending portions of said sections.

3. The structure in claim 2 and, said extending portions of said wrist encircling belt sections lying along said main belt and extending away from each other.

4. In a restraining device for anesthesia and surgery, a main restraining belt, a pair of closely spaced wrist encircling belt sections, each of said sections having an end secured to said main belt, said sections having their ends passed through said main belt through apertures lying diagonally across said main belt, said sections being slidably through said apertures, those portions of said sections extending through said main belt lying substantially flat against the main belt, and separable fasteners detachably connecting said extending portions of said sections to said main belt, and said fasteners being separable in a direction substantially transversely to said main belt and said extending portions of said sections.

5. The structure in claim 1 and, said wrist encircling sections being spaced a considerable distance apart to permit the restraining of the hands and the arms of a patient at the side of the body.

6. The structure in claim 1 and, said extending portions of said belt sections lying with their fastener secured ends directed toward each other.

7. The structure in claim 1 and, said main belt having apertures to receive said extending portions of said sections, and said apertures lying substantially at right angles to the length of said main belt.
